UNITED STATES PATENT OFFICE

154,421

DESIGN FOR A COMMEMORATIVE CANDLEHOLDER

William Niederhausen and Conrad Dallwin
Hamilton, New York, N. Y.

Application August 21, 1947, Serial No. 140,984

Term of patent 3½ years

(Cl. D48—2)

To all whom it may concern:

Be it known that we, William Niederhausen, a citizen of Germany, who has declared his intention of becoming a citizen of the United States, and Conrad Dallwin Hamilton, a citizen of the United States, each residing at New York, in the county of New York and State of New York, have invented a new, original, and ornamental Design for a Commemorative Candle Holder, of which the following is a specification, reference being had to the accompanying drawing, forming a part thereof.

Fig. 1 is a front elevational view of a commemorative candle holder, showing my design,

Fig. 2 is a top plan view thereof, and

Fig. 3 is a side elevational view thereof.

The back of the commemorative candle holder is substantially plain.

We claim:

The ornamental design for a commemorative candle holder, substantially as shown and described.

WILLIAM NIEDERHAUSEN.
CONRAD DALLWIN HAMILTON.
